PRESSURE RESPONSIVE DEVICE

Herbert C. Kellogg, Detroit, Mich., assignor to
 Glen P. Cowan, Detroit, Mich.; Grace A.
 Cowan executrix of Glen P. Cowan, deceased

Application January 23, 1931. Serial No. 510,702

8 Claims. (Cl. 50—14)

This invention is a continuation in part of my co-pending application Serial No. 328,268, filed December 24, 1928, and relates to pressure responsive devices, and in particular to devices embodying an expansible chamber that is adapted to respond to fluid pressures for the actuation of mechanism operatively associated therewith.

It is often necessary or desirable in the class of devices to which the invention relates, to have means for readily varying the operating characteristics of the device, and it is one of the objects of this invention to provide a pressure responsive device that may be readily adjusted to operate over various pressure ranges and under predetermined operating conditions.

Another object is to provide an improved form of pressure responsive device in which the gradual movement of an expansible contractible element is transformed into a snap action movement.

Another object of this invention is to provide a device of the class described that can be easily and inexpensively manufactured and assembled, and that has a minimum number of parts which are relatively rugged and do not require complicated machining operations for their manufacture.

A further object of this invention is to provide a device of the type described in which a single expansible contractible element serves as an operating means and as an adjustment means for the mechanism with which it is to be associated.

With the above and other objects in view which will be apparent from the following description, the present invention consists in certain features of construction and combinations of parts which will be readily apparent to those skilled in the art to which the invention appertains.

Referring to the drawing in which a suitable embodiment of the invention is illustrated,

Figure 1 represents a typical set-up of a pair of refrigeration evaporators controlled by my improved pressure responsive device;

Fig. 2 is a fragmentary enlarged section through the valve mechanism showing the valve in open position;

Fig. 3 is a section similar to Fig. 2 with the exception that the valve is shown in its closed position; and

Fig. 4 is a section similar to Figs. 2 and 3 only showing the position of the valve parts substantially at the initial opening of the valve.

As an exemplification and an illustration of one of the practical uses which can be made of

my invention, I have shown it embodied in a control valve for mechanical refrigerators of the flooded system type using a multiplicity of evaporators connected to a single pump and adapted to maintain different predetermined temperatures under the control of my improved valve.

In any refrigerating machine operating on the compression system, there are four distinct steps in the cycle of the refrigerant; compression, condensation, reduction of pressure, and evaporation. In refrigerators operating on the flooded system, the four steps in the cycle of the refrigerant are first, heat-laden gas, which is at low pressure and temperature level, is pumped from the top of the float valve housing of the freezing coil unit by the compressor and compressed to a high pressure and hence high temperature level. Second, the high pressure, high temperature gas which the compressor delivers to the condenser gives up its heat to the surrounding air and condenses to a liquid which is still under high pressure. Third, the high pressure liquid is carried to the float valve which admits the liquid to the freezing or evaporating coils, filling them completely. This reduces the pressure of the liquid to a low pressure and hence low temperature level. Fourth, the low pressure, low temperature liquid as it receives heat in the freezing coils, evaporates to a low pressure gas. As the gas forms in the freezing coils it rises through the liquid and collects in the top of the valve housing.

Referring to the accompanying drawing in which like numerals refer to like parts throughout the several views, and to Fig. 1 of such a refrigerating system in particular, the numeral 1 indicates the suction line to the conventional compressor (not shown). The compressor is in turn connected to a series of cooling coils (not shown) into which the gas is pumped and condensed by the increase in pressure and the loss of heat in the condenser. From the condenser coils, liquid refrigerant is usually led to a liquid reservoir (not shown) which in turn communicates with the high pressure liquid line 2 of Fig. 1.

The high pressure liquid in the line 2 is led to two float valves indicated by the numerals 3 located at the inlet side of the evaporator coils 4 and 5. A control valve 6 is located in the suction line 1 at a point close to the evaporator 4. The purpose of the valve 6 is to maintain predetermined temperature in the coils to which they are connected. The manner in which this

is accomplished will be presently described in detail.

The compressor, cooling or condensing coils, liquid reservoir and automatic mechanism governing the operation of the compressor may be of any suitable type. These elements are not illustrated because they do not form a part of this invention, and at present are not necessary for its understanding.

10 Referring to Figs. 2, 3 and 4, which illustrate the structural details of the control valve 6, the numeral 9 indicates a valve body, the upper portion of which threadably receives a cylindrical housing 10 that threadably carries a cap 11. 15 The housing 10 and cap 11 provide a housing for an expansible contractile element or bellows 12, the upper end of which is sealed by a disc 13. The lower end of the bellows 12 is sealed by the top of the valve body 9. The disc 13 is movable within the housing 10, its upward position being limited by a boss 14 formed on the cap 11 and being resisted by a coil compression spring 15 surrounding the boss 14 and extends between the cap 11 and disc 13. A conical 20 shaped cam 16 is threadably secured in the central portion of the disc 13 and cooperates with a pair of rollers 17 that are rotatably mounted on suitable resilient supporting pins 18 carried in the end of a cylindrical valve head guide 19, 25 which is integrally formed with the valve head 20. The disc 13 is also provided with a central guide pin 21 which is slidably received within an opening formed in the boss 14.

Excessive downward movement of the disc 13 30 is limited by a cylindrical stop 26 surrounding the rollers 17 and mounted on the top of the body 9. Interposed between the cylindrical stop 26 and the bellows 12 is a coil compression spring 27 which engages the valve body 9 and under 35 side of the disc 13 to provide a cushion action, the spring 27 being of lesser resistance than the spring 15.

The valve body 9 is provided with an inlet 40 opening 23 and an outlet opening 24 which lead into a valve chamber 22 extending through the body 9. The valve head and valve seat are tapered and of such size to provide an opening equivalent to the size of the conduit 1. A passage 25 is formed in the valve head 21 and its 45 guide 19 to permit the fluid under pressure at the inlet side of the valve to flow into the interior of the bellows 12 and act against the disc 13 and thereby expand the bellows 12. The lower end 50 of the valve body 9 is closed by a suitable clean-out plug 28, and this plug at the point where the valve head 20 seats against it in open position as shown in Fig. 2, is recessed at 29 to permit the flow of fluid to the under side of the 55 valve head 20 and thence through the passage-way 25.

It will be observed that variations in the fluid pressure acting against the disc 13 will cause the bellows 15 to expand or contract in accordance with the opposing pressure of the spring 15. The 60 pressure of the spring 15 may be manually adjusted by raising or lowering the housing 10 by rotating the same. The motion of the bellows is transmitted to the snap action mechanism, causing the valve head 20 to move to a fully open or 65 fully closed position as the high part of the cam 16 passes the plane of the axes of the spring held roller 17 in moving upwardly or downwardly.

When used in connection with a refrigeration 70 system of the type shown, the purpose of any of

the valves is to control the temperature of the evaporator or evaporators where more than one valve is used, by means of the pressure in the evaporator to which the valve is connected, such as where it is desired to prevent the temperature 80 from going below a predetermined point.

The valve is so designed as to take advantage of the increased suction pressure on any of the evaporators operating under high temperatures. This is accomplished by a quick opening and a 85 quick closing action of the valve, so that when gas is being removed from an evaporator the valve controlling the temperature or pressure will be wide open. This action results in increased pressure to the compressor with an 90 increase in the capacity.

Valves heretofore were designed as pressure reducing valves and consequently did not increase the suction line pressure to the compressor when gas was being taken from the 95 evaporator.

The snap action on the valve is also desirable as such an action assists in keeping the valve clear of foreign material which might become lodged between the valve and seat, causing it to 100 leak. The valve in this design is balanced to prevent a change in maintained pressures with widely varying control settings.

The valve proper is so designed that it may be readily removed through the opening closed by 105 the plug 28 or reseated. With its removal, all working parts which it may be desirable to replace are easily removable. The valve is exceedingly simple in construction, compact in 110 size and easily adjusted.

As a matter of explanation, we will assume that the valve is used in connection with a soda fountain where an evaporator such as 5 is adapted to be maintained at ice cream temperatures at approximately zero degrees, and that the evaporator 4 is to be maintained at approximately 115 20 degrees. We will further assume that the compressor is running, and that the temperature of the evaporator 4 is above 20 degrees. Under these conditions the valve head 120 20 is in open position, as shown in Fig. 2. As the pressure in the evaporator 4 is being reduced, the bellows 12 is collapsing because of this reduction of pressure, and when the pressure is reduced to a point which corresponds to 20 degrees 125 the bellows collapses to substantially its minimum, at which time the cam 16 spreads the rollers 17 apart by reason of the resiliency of the spring supports, and as the widest portion of the cam passes the center line of the rollers the resiliency of the spring pins 18 causes the rollers 17 130 to move along the upper surface of the cam, thereby quickly moving the valve head to its closed position against the seat as shown in Fig. 3. This closes the suction line to the evaporator 135 4 and permits the compressor to continue its cooperation with the evaporator 5. As the evaporator 4 warms up, pressure in the suction line increases and this pressure is transmitted through the recesses 29 in the plug 28 to the 140 passage 25 in the valve head 20 and guide 19 and thence through the small opening therein into the interior of the bellows 12. This pressure when greater than the difference between the predetermined pressure of the springs 15 and 27, 145 acts against the bellows head disc 13, thus causing the bellows to expand.

During this expansion, the cam 16 moves relative to the rollers 17 since the valve head 20 is seated against further movement in that direc- 150

tion, and at the instant that the high points of the cam pass the center line of the rollers the rollers, because of the resiliency of the pin supports 18, slide along the lower conical surface of 5 the cam and thereby quickly move the valve head 20 to its open position, as shown in Fig. 6. The position of the operating parts at the initial opening of the valve is shown in Fig. 4. In 10 other words, the rollers 17 spring past the dead center position of the cam 16 when the pressure within the bellows has increased sufficiently, thereby quickly pushing the valve 20 to its open position. This operation may be repeated several 15 times while the compressor is still operating in connection with the evaporator 5.

Now we will assume a condition in which the evaporator 5 is at the desired temperature and the temperature of the evaporator 4 is above the set temperature of 20 degrees. In this case the 20 compressor is not in operation since it is controlled by the temperature of the evaporator 5 which is at zero degrees. In this case the valve mechanism opens in the same manner as previously described, because of the increase in pressure 25 in the suction line. This then opens the connection between the two evaporators, thus equalizing the pressures therein and equalizing the temperatures. If this equalized pressure is greater than the pressure from which the controlling 30 mechanism is set to place the compressor in operation, it will consequently cause the pump to again be set in operation and the valve to be closed when the pressure corresponding to 20 degrees is reached, as previously described. The 35 compressor will then operate until the pressure within the evaporator 5 has again reached the pressure corresponding to the temperature of zero degrees that is to be maintained in the evaporator 5.

40 This quick opening and quick closing action on the part of the control valve described will materially increase the capacity of the compressor employed, particularly where a high percentage of the total load must be handled by the higher temperature evaporator.

45 It is obvious that when a different temperature is to be maintained in the evaporator 4, the valve can be set to correspond to the desired temperature by merely rotating the housing 10 to increase or decrease the pressure of the spring 15 as the case may be.

Furthermore, it is to be understood that the 55 particular form of apparatus shown and described, and the procedure set forth are presented for purposes of explanation and illustration, and the various modifications of the apparatus and procedure can be made without departing from my invention as defined in the appended claims.

50 What I claim is:

1. In a pressure responsive valve, a valve body having a valve chamber therein, inlet and outlet 55 passages opening into said chamber, a valve seat in said chamber interposed between said passages, one end of said chamber being open and the other end being closed, an expansible-contractible bellows member closed at one end and secured at its opposite end to said body to 60 enclose said open end of said chamber, a reciprocable guide in said chamber between said passages and the open end of said chamber and having a sliding fit with the walls of said chamber, a reciprocable valve head carried by said guide and being cooperatable with said seat to 65 permit open communication and completely pre-

vent communication between said passages, a passage through said valve head providing communication between the interior of said bellows and said inlet passage, and snap action mechanism between said valve head and the closed end of said bellows for providing rapid movement of said valve head relative to said seat upon expansion or contraction of said bellows by the pressure of the fluid in said inlet passage.

2. In a pressure responsive valve, a valve body having a valve chamber therein, inlet and outlet passages opening into said chamber, a valve seat in said chamber interposed between said passages, one end of said chamber being open and the other end being closed, an expansible-contractible bellows member closed at one end and secured at its opposite end to said body to enclose said open end of said chamber, spring means for yieldably resisting expansion of said bellows, a reciprocable guide in said chamber between said passages and the open end of said chamber and having a sliding fit with the walls of said chamber, a reciprocable valve head carried by said guide and being cooperatable with said seat to permit open communication and completely prevent communication between said passages, a passage through said valve head providing communication between the interior of said bellows and said inlet passage, and snap action mechanism between said valve head and the closed end of said bellows for providing rapid movement of said valve head relative to said seat upon expansion or contraction of said bellows by the pressure of the fluid in said inlet passage.

3. In a pressure responsive valve, a valve body having a valve chamber therein, inlet and outlet passages opening into said chamber, a valve seat in said chamber interposed between said passages, one end of said chamber being open and the other end being closed, an expansible-contractible bellows member closed at one end and secured at its opposite end to said body to enclose said open end of said chamber, spring means for yieldably resisting expansion of said bellows, means for increasing or decreasing the pressure of said spring means, a reciprocable guide in said chamber between said passages and the open end of said chamber and having a sliding fit with the walls of said chamber, a reciprocable valve head carried by said guide and being cooperatable with said seat to permit open communication and completely prevent communication between said passages, a passage through said valve head providing communication between the interior of said bellows and said inlet passage, and snap action mechanism between said valve head and the closed end of said bellows for providing rapid movement of said valve head relative to said seat upon expansion or contraction of said bellows by the pressure of the fluid in said inlet passage.

4. In a pressure responsive valve, a valve body having a valve chamber therein, inlet and outlet 140 passages opening into said chamber, a valve seat in said chamber interposed between said passages, one end of said chamber being open and the other end being closed, an expansible-contractible bellows member closed at one end and secured at its opposite end to said body to enclose said open end of said chamber, means for 145 axially guiding the closed end of said bellows during movement thereof, a reciprocable guide in said chamber between said passages and the open end of said chamber and having a sliding fit with the walls of said chamber, a reciprocable 150

- valve head carried by said guide and being cooperatable with said seat to permit open communication and completely prevent communication between said passages, a passage through 80
- 5 said valve head providing communication between the interior of said bellows and said inlet passage, and snap action mechanism between said valve head and the closed end of said bellows for providing rapid movement of said valve 85
- 10 head relative to said seat upon expansion or contraction of said bellows by the pressure of the fluid in said inlet passage.
5. In a pressure responsive valve, a valve body having a valve chamber therein, inlet and outlet 90
- 15 passages opening into said chamber, a valve seat in said chamber interposed between said passages, one end of said chamber being open and the other end being closed, an expansible-contractible bellows member closed at one end and 95
- 20 secured at its opposite end to said body to enclose said open end of said chamber, spring means for yieldably resisting expansion movement of said bellows, means for decreasing or increasing the pressure of said spring means, 100
- 25 means for axially guiding the closed end of said bellows during movement thereof, a reciprocable guide in said chamber between said passages and the open end of said chamber and having a sliding fit with the walls of said chamber, a reciprocable valve head carried by said guide and being cooperatable with said seat to permit open communication and completely prevent communication between said passages, a passage through said valve head providing communication between the interior of said bellows and said inlet passage, and snap 105
- 30 action mechanism between said valve head and the closed end of said bellows for providing rapid movement of said valve head relative to said seat upon expansion or contraction of said bellows by the pressure of the fluid in said inlet 110
- 35 passage.
35. In a pressure responsive valve, a valve body having a valve chamber therein, inlet and outlet 115
- 40 passages opening into said chamber, a valve seat in said chamber interposed between said passages, one end of said chamber being open and the other end being closed, an expansible-contractible bellows member closed at one end and secured at its opposite end to said body to enclose said open end of said chamber, a closed housing carried by said body to surround said body, telescoped relatively movable cooperating parts carried by said housing and the closed end of said bellows for axially guiding the closed end of said bellows during movement thereof, a reciprocable guide in said chamber between said passages and the open end of said chamber and having a sliding fit with the walls of said chamber, a reciprocable valve head carried by said guide and being cooperatable with said seat to permit open communication and completely prevent communication between said passages, a passage through said valve head providing communication between the interior of said bellows and said inlet passage, and snap action mechanism between said valve head and the closed 120
- 50 end of said bellows for providing rapid movement of said valve head relative to said seat upon expansion or contraction of said bellows by the pressure of the fluid in said inlet passage.
55. In a pressure responsive valve, a valve body having a valve chamber therein, inlet and outlet 125
- 60 passages opening into said chamber, a valve seat in said chamber interposed between said passages, one end of said chamber being open and the other end being closed, an expansible-contractible bellows member closed at one end and secured at its opposite end to said body to enclose said open end of said chamber, a closed housing carried by said body to surround said body, telescoped relatively movable cooperating parts carried by said housing and the closed end of said bellows for axially guiding the closed end of said bellows during movement thereof, a reciprocable guide in said chamber between said passages and the open end of said chamber and having a sliding fit with the walls of said chamber, a reciprocable valve head carried by said guide and being cooperatable with said seat to permit open communication and completely prevent communication between said passages, a passage through said valve head providing communication between the interior of said bellows and said inlet passage, and snap action mechanism between said valve head and the closed 130
- 65 end of said bellows for providing rapid movement of said valve head relative to said seat upon expansion or contraction of said bellows by the pressure of the fluid in said inlet passage.

HERBERT C. KELLOGG.
